Tinsmith.

UNITED STATES PATENT OFFICE.

MOSES F. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,300,585.

Specification of Letters Patent. Patented Apr. 15, 1919.

Application filed September 14, 1917. Serial No. 191,484.

To all whom it may concern:

Be it known that I, MOSES F. CARR, a citizen of the United States, and a resident of Newton, in the county of Middlesex, Commonwealth of Massachusetts, (whose post office address is care of Carr Fastener Company, Cambridge, Massachusetts,) have invented an Improvement in Fasteners, of which the following description, in connection with the accompanying drawings, is a specification, like characters on the drawings representing like parts.

This invention pertains to improvements in stud and socket fasteners. Among the objects of the invention is to provide a stud and socket fastener wherein the number of parts is reduced to a minimum.

In the drawings:

Figure 1 is a front elevation of a preferred form of fastener constituting one embodiment of my invention;

Fig. 2 is a section thereof on the line 2—2 of Fig. 1;

Fig. 3 shows the casing of the socket proper and is more fully described hereafter;

Fig. 4 is an elevation of a preferred form of clench plate for use in connection with my invention.

Referring to the drawings, I have shown a stud 5, having a head 6 and a recessed portion or neck 7. The preferred form of socket herein shown comprises a casing 8, preferably died from a single piece of metal 30 to support on all sides jaw means herein shown as jaws 9, 10 formed from a single piece of wire 13. The casing 8 is preferably died to provide relatively short prongs 14 for holding the outside portions of the 35 spring wire 13 in the casing 8, and to provide the transverse portions 15, 16 to support one side of the jaws 9, 10 while the other side of the jaws 9, 10 is supported by front portions 17, 18. The center of the 40 casing is died inwardly to provide an aperture and a support 19 to receive and support the head 6 of the stud with the jaw means of the socket engaging the recessed portion of the stud. The preferred form of 45 socket casing is preferably utilized on the same side of the fabric 20 that the stud 5 is located on, thereby rendering it unnecessary to cut the fabric 20 to allow the head of the stud 5 to pass therethrough. To this end I 50 may, and preferably do, provide a front 55

plate 21, preferably died outwardly at the center as shown, and preferably providing prongs 22 adapted to pierce the fabric 20 and to be clenched on the back of the casing portion of the socket.

60

While I have shown and described one embodiment of my invention, it will be understood that changes involving substitution, omission, alteration and reversal of parts may be made without departing from the scope of my invention, which is best defined in the following claims.

65

Claims:

1. A socket for stud and socket fasteners having a spring jaw, and a casing therefor formed of a single sheet of metal to support opposite sides of said jaw and to provide an extended support for the stud both forwardly and rearwardly of said jaw.

70

2. A socket for stud and socket fasteners comprising, in combination, a spring jaw, a casing therefor formed of a single sheet of metal to provide a support for opposite sides of said jaw, and to provide an extended support for the stud both forwardly and rearwardly of said jaw, said casing and jaw being applied to the same side of the fabric from whence the stud enters.

75

3. A socket for stud and socket fasteners comprising, in combination, a spring jaw, a casing therefor formed of a single sheet of metal to provide a support for opposite sides of said jaw, said casing and jaw being applied to the same side of the fabric from whence the stud enters, and a plate for application to the opposite side of the fabric, and having prongs projecting therefrom and bent inwardly over the extreme outside edges of said casing to hold the same in determined position on the fabric.

80

90

4. A socket for stud and socket fasteners having a casing for application to the same side of the fabric from which the stud enters, said casing containing a spring jaw and being formed of a single sheet of metal to provide support to opposite sides of said spring jaw, and to provide a stud support permitting tipping movement of said stud relative to said casing in one direction only.

95

5. A socket for stud and socket fasteners comprising, in combination, jaw means, a casing 8 having supports 15, 16 for one side of the jaw means, supports 17, 18 for the other side of the jaw means and a stud supporting element 19.

100

105

110

6. A socket for stud and socket fasteners comprising, in combination, a casing 8 containing spring jaw means and died from a single sheet of metal to provide offset supports 19, 16 for the stud.

7. A socket for stud and socket fasteners comprising, in combination, a casing for spring jaw means, said casing being formed of a single sheet of metal to provide a lip 10 16 for engagement with the stud on one side

of said casing, and a support 19 for engagement with the stud on the opposite side of said casing whereby relative tipping movement of said stud and socket is permitted in one direction while being prevented in all other directions. 15

In testimony whereof, I have signed my name to this specification.

MOSES F. CARR.
